WITNESS:

O. Hildremyr, INVENTOR
BY Victor J. Evans
ATTORNEY

UNITED STATES PATENT OFFICE.

OLE HILDREMYR, OF PETERSBURG, NORTH DAKOTA.

GATE.

Application filed December 31, 1921. Serial No. 526,273.

To all whom it may concern:

Be it known that I, OLE HILDREMYR, a citizen of the United States, residing at Petersburg, in the county of Nelson and State of North Dakota, have invented new and useful Improvements in Gates, of which the following is a specification.

This invention relates to gates such as are used in farm yard fences and the like, and has for its object the provision of a gate so constructed that it may be slid along the fence with which it is associated instead of being swung as in the ordinary manner, the gate being provided with operating means whereby it will be automatically moved to open or closed position as the case may be upon the approach of a vehicle toward the gate or departure of the vehicle after passing through the gate.

An important and more specific object is the provision of a gate of this character which is so constructed and mounted as to have a pivot point, this pivot point being raised or lowered, as the case may be, upon the approach of a vehicle or departure thereof so that the elevation of the pivot point will cause the gate to gravitationally slide either to open or closed position.

A further object is the provision of a gate of this character which is constructed entirely of metal and which is so formed that sagging thereof will be prevented under all conditions, the gate being associated with and supported by a plurality of rollers carried by supporting posts so that the action will be free and unimpeded.

An additional object is the provision of a gate of this character which will be simple and inexpensive, in manufacture and installation, highly efficient in use, durable in service and a general improvement in the art.

With the above and other objects and advantages in view, the invention consists in the details of construction to be hereinafter more fully described and claimed, and illustrated in the accompanying drawings in which,

Figure 1 is a side elevation of my gate showing it in closed position.

Figure 2 is a similar view showing it in open position.

Figure 3 is a cross sectional view taken to show an elevation of one of the supporting members.

Figure 4 is a cross sectional view on the line 4-4 of Figure 1.

Figure 5 is a detail plan view of one of the treadle members.

Referring more particularly to the drawings, in carrying out my invention I provide a gate post 10 with which are connected the usual line wires 11 of the fence and at a spaced point I provide a gate post 12, of special construction to be hereinafter described, with which the line wires 11 at the other side of the gate opening are also secured. At a point spaced from the post 12 I provide a pair of upright posts 13 which are somewhat spaced apart and which have their lower ends preferably anchored within concrete blocks 14. Secured between the upper ends of the upright which constitutes the second mentioned posts is journaled a transversely disposed roller 15 which extends entirely across the space between the two uprights 13. Also journaled upon the confronting faces of the upright 13 are separate rollers 16 arranged in straight relation. In actual practice it is preferable that these uprights 13 be formed of angle iron though it is conceivable that they might be formed of something else if preferred.

The post structure 12 comprises a pair of uprights 17 which are likewise preferably formed of angle iron and slidably mounted between these uprights 17 is an elongated rectangular frame 18 within the upper portion of which is mounted a transverse roller 19 and upon the confronting faces of the sides of which are journaled separate rollers 20. The rollers 19 and 20 corresponding to the rollers 15 and 16 of the post structure 13 as will be readily apparent from an inspection of the drawings.

Pivotedly mounted upon the uprights 17 are angle levers 21. Located at opposite sides of the gate opening are treadle members which are similar in construction and each of which may be formed from a single bar bent into a shape similar to that of a crank shaft and including crank portions 23 and 24 which are disposed within the wagon track, that is in the path of the wheels of a vehicle approaching the gate opening, and these rods are also formed at their end portions with cranks 25 which are pivotally connected with the adjacent angle levers 21 by means of links or pitmen 26.

The gate itself comprises a pair of bars 27 of angle shape secured together whereby to provide outwardly extending flanges 28 which are disposed between the rollers 20 and 19 and 16 and 15 so that the gate will be properly supported by these rollers. The gate further includes a bottom bar 29, an end bar 30 and a rear upright or end bar 31. The gate further includes an inclined brace bar 32 which leads from the lower end of the bar 31 to the rear extremity of the combined bars 27 and also includes vertically disposed brace bars 33, an inclined brace bar 34 connected with the bar 32, and with the bar 27. The numeral 35 designates diagonal brace bars which are arranged in cross relation as shown and which are for the purpose of preventing the gate structure from sagging. While the gate is referred to as consisting of bars other than those 27 it is of course to be understood that in actual practice gas pipes may be found to be an unusually satisfactory material from which the structure may be formed.

Secured upon the gate post 10 is a U-shaped retaining member 36 adapted to embracingly receive the end post 30 of the gate and also secured upon the gate post 10 is a lower retaining member which is formed somewhat in the nature of a catch and which is formed with a slot 38 of angular shape within which is received a pin 39 projecting from the end member 30 of the gate.

The operation of the gate is as follows; under ordinary conditions the gate is in the position shown in Figure 1, that is it extends entirely across the gate opening with the end bar 30 engaged within the member 36, the pin 39 on the end member of the gate being engaged within the slot 38 as clearly shown. When a vehicle approaches the gate from either side and the wheels of the vehicle engage against the crank portion 23 of the operating member it will be seen that a force will be exerted upon the link 26 which will result in swinging movement of the associated angle lever 21, whereupon this lever engaging the frame 18 will cause the frame 18 to be moved upwardly between the support 17. As this frame 18 moves upwardly it will be apparent that it will tilt the gate so that the forward or free end thereof will be higher than the rear end. The gate will then slide to open position, owing to the fact that the combined upper bars 27 are slidably engaged upon the rollers 16 and 20. This action of the gate is effected by gravity alone and it will be seen that the gate will naturally and automatically slide to its open position. After the vehicle has passed through and the wheels thereof engage the crank portion 24 at the opposite side of the gate, it will be seen that the link 26 at the opposite side of the gate will be operated to swing the associated levers 21 downwardly whereupon

the frame 18 will be moved downwardly between the supports 17 and this will result in overbalancing the weight in the opposite direction so that the gate will automatically slide into closed position as shown in Figure 1.

From the foregoing description and a study of the drawings it will be apparent that I have thus provided a simply constructed and easily installed gate which will be inexpensive in manufacture and which will be highly efficient and positive in operation, regardless of whether the ground is clear or whether the way be obstructed by snow or the like. It will be observed that there is no necessity for providing a wide smooth arc through which the gate may swing as the gate merely slides along the fence with which it is associated. In winter time it is therefore obvious that it is unnecessary to shovel away the snow as when the gate is initially opened it will easily cut its own way through. It is likewise to be observed that owing to the simplicity of the construction that there is practically nothing to get out of order and the device shall consequently have an extremely long life.

While I have shown and described the preferred embodiment of the invention, it is of course to be readily understood that I reserve the right to make such changes in the form, construction and arrangement of parts as will not depart from the spirit of the invention or the scope of the claims.

Having thus described my invention I claim:

1. A gate and operating mechanism therefor comprising a post disposed at one side of a gate opening, a post disposed at the opposite side of the gate opening and formed as a pair of spaced uprights, a roller journaled between and extending entirely across the upper end of said uprights, a pair of rollers disposed against the confronting sides of said uprights in spaced relations to said first named roller, a third post disposed between said first and second named posts and formed as a pair of spaced uprights, a rectangular elongated frame disposed between and slidably mounted between said second named pair of uprights, a roller journaled transversely of said frame at the upper end thereof, a pair of rollers journaled upon the confronting sides of said frame in spaced relation to the first named roller therein, a gate including an upper bar of angle formation including horizontal flanges beneath said first named rollers of the second and third named posts and engaging upon the last named rollers of the second and third named posts, and means for moving said frame.

2. A gate and operating mechanism therefor comprising a post disposed at one side of a gate opening, a post disposed at the op-

posite side of the gate opening and formed as a pair of spaced uprights, a roller journaled in and extending between the upper ends of said uprights, a pair of rollers disposed against the confronting sides of said uprights in spaced relation to said first named roller, a third post disposed between said first and second named posts and formed as a pair of spaced uprights, a rectangular elongated frame disposed between and slidably mounted between said second named pair of uprights, a roller journaled transversely of said frame at the upper end thereof, a pair of rollers journaled upon the confronting sides of said frame in spaced relation to the first named roller therein, a

gate including an upper bar of angle formation including horizontal flanges engaged beneath first named rollers of the second and third named posts and engaging 20 upon the last named rollers of the second and third named posts, angle levers pivoted upon said last named uprights and engaging the lower end of said frame, links connected with said angle levers and extending 25 to opposite sides of the gate and treadle members of crank like formation pivoted upon opposite sides of the gate opening and having crank arms connected with said links.

In testimony whereof I affix my signature. 30

OLE HILDREMYR.
